US00D901246S

(12) **United States Design Patent** (10) Patent No.: **US D901,246 S**
(45) Date of Patent: **** Nov. 10, 2020**

(54) **ACCESSORY FOR MACHINERY AND APPARATUS FOR THE PREPARING OF FOOD AND DRINK**

(71) Applicant: **Vorwerk & Co. Interholding GmbH**, Wuppertal (DE)

(72) Inventors: **Uwe Kemker**, Wuppertal (DE); **Felix Thies**, Wuppertal (DE)

(73) Assignee: **Vorwerk & Co. Interholding GmbH**, Wuppertal (DE)

(**) Term: **15 Years**

(21) Appl. No.: **29/664,481**

(22) Filed: **Sep. 25, 2018**

(30) **Foreign Application Priority Data**

Mar. 28, 2018 (EM) 005134830-0001

CLAIM

The ornamental design for accessory for machinery and apparatus for the preparing of food and drink, as shown and described.

DESCRIPTION

FIG. 1 is a top perspective view of the accessory for machinery and apparatus for the preparing of food and drink showing our new design;

FIG. 2 is a front view thereof;

FIG. 3 is a back view of thereof;

FIG. 4 is a right side view thereof;

FIG. 5 is a left side view thereof;

FIG. 6 is a top view thereof; and,

(Continued)

FIG. 7 is a bottom view thereof.

1 Claim, 3 Drawing Sheets
